(57) **CLAIM**

The ornamental design for a tether for baby, infant and child products, as shown and described.

DESCRIPTION

FIG. 1 is a top view of a tether for baby, infant and child products showing our new design;
FIG. 2 is a front view of FIG. 1;
FIG. 3 is a bottom view of FIG. 1;
FIG. 4 is a back view of FIG. 1;
FIG. 5 is a left-side view of FIG. 1;
FIG. 6 is a right-side view of FIG. 1;
FIG. 7 is a top perspective view of FIG. 1;
FIG. 8 is a bottom perspective view of FIG. 1;
FIG. 9 is an exploded top view of FIG. 1;
FIG. 10 is an exploded front view of FIG. 9;
FIG. 11 is an exploded bottom view of FIG. 9;
FIG. 12 is an exploded back view of FIG. 9;
FIG. 13 is an exploded left-side view of FIG. 9;
FIG. 14 is an exploded right-side view of FIG. 9;
FIG. 15 is an exploded top perspective view of FIG. 9; and,
FIG. 16 is an exploded bottom perspective view of FIG. 9. Any portion between the break lines forms no part of the claimed design.
